UNITED STATES PATENT OFFICE.

RHETHERFORD B. MARTIN, OF NEW YORK, N. Y., ASSIGNOR TO MINERALS SEPARA-
TION NORTH AMERICAN CORPORATION, OF NEW YORK, N. Y., A CORPORATION OF
MARYLAND.

PRODUCTION OF OXIDIZED CARBON COMPOUNDS.

Application filed June 3, 1921. Serial No. 474,810.

To all whom it may concern:

Be it known that I, RHETHERFORD B. MARTIN, a citizen of the United States, and a resident of the borough of Manhattan, city and State of New York, have invented certain new and useful Improvements in the Production of Oxidized Carbon Compounds, of which the following is a specification.

This invention relates to oxidized carbon compounds and is herein described as applied to the incomplete or partial oxidation of petroleum products with the production of various substances or compositions, especially such as are adapted among other things to serve as mineral-frothing agents. I have discovered that such substances as petroleum distillates can be readily oxidized by diluted oxygen in the form of air, with very accurate control of the conditions of oxidation and consequent uniformity and efficiency in the product, if the oxidation is effected in a confined space in the presence of carbonaceous material, especially if hard, such as ground coke or powdered charcoal. A test run with manganese peroxide in place of coke, and heated until pasty, yielded a product similar to the product obtained when using coke or charcoal.

Apparently when using a paraffin gas oil as a raw material for such a product, the most satisfactory product for the froth flotation concentration of many ores is obtained by so controlling conditions as to obtain a product absorbable to about 65 or 70 per cent in concentrated sulphuric acid, and the description herein given in some detail is more particularly directed to the obtaining of such a product. Suitable condensing arrangements may be provided and it may be sometimes found advantageous to collect the somewhat more volatile portions of the product in separate condensers or collectors of a series, since the product first condensed appears to have mineral-frothing values somewhat inferior to the product carried past a first condenser but condensed readily in a second condenser. Apparently the presence of water vapor in the vaporized oil is advantageous when a mineral-frothing agent is the desired product. To obtain this result, water or steam may be introduced with the oil.

In the accompanying drawing is shown diagrammatically an apparatus which has

been found suitable for carrying out the present invention. An oil such as paraffin gas oil is fed through a valved tube or pipe 1 so that it runs in a small stream, or may even drop through the upper open end 2 of a retort 3. The retort 3 was made of ordinary 2-inch iron pipe forming a center section 4, screwed into upturned elbows 5 which formed end sections, the opening 2 being formed by screwing reducers 6 into the elbow so that the oil coming from the tube 1 dropped in through an opening $\frac{1}{2}$ -inch in diameter thus controlling the admission of air. Under these conditions, with the air pump shown at 7 which was used, it was found that the oil was satisfactorily volatilized and was oxidized to the desired degree by the incoming air when the bottom of the section 4 of the retort 3 was nearly but not quite half filled with powdered coke or powdered charcoal maintained at a suitable temperature by a burner shown diagrammatically at 8. The exit end 9 of the retort was formed of an upwardly extending pipe 10 like the pipe 3 and was found satisfactory when about a foot in length and provided with a smaller exit pipe 11, say $\frac{1}{2}$ -inch pipe, which was bent over at an elbow 12 and led into a retort 13 which formed a first air cooled condenser. Under these conditions the retort 3 was found to work satisfactorily when 7 inches long between vertical centers of the elbows 5.

It was found advisable to feed oil at a rate of 38 or 40 cc. per minute when using coke or powdered charcoal in the retort 3. To avoid ignition of the oil at the beginning of a run the oil should be fed rather rapidly or with some water, the latter, as stated above, sometimes being advantageous, but when used in excessive quantities resulted in the production of an emulsion in the condensing vessels which was very difficult to separate. To observe temperatures a pyrometer 14 was inserted in the vertical section 10 of the retort and extended substantially down to the upper end of the exit end elbow 5. This pyrometer showed that the best product for use as a mineral-frothing agent was obtained from a coke filled retort when the temperature was about 400° C. and from a charcoal filled retort when the temperature was about 350° C. It was noted that the temperature shown by the pyrometer was

considerably higher when oil was being drawn through the retort than when air alone was being drawn through. To insure uniformity of heating, the retort 3 was placed in a loose brickwork 26 and in operation was usually heated by a Bunsen burner.

The product which passed on in vapor form through the condensing retort 13 was carried by a tube or pipe 15 to a twin-necked condensing bottle 16 provided with a return condenser 17 at its exit end, which in turn was connected by a tube 18 to a second twin-necked bottle 19 provided with a scrubbing return condenser 20. From the scrubber 20 a tube 21 carried the still volatile parts of the product to an air pump 7, shown diagrammatically as a fan, which was connected by an exit pipe 22 to a species of filter pump 23, so that the effluent gases were absorbed by water coming from a tap 24 which fed the filter pump. The water containing the gases could be observed in the sink 25. It was found that the best mineral-frothing agent was collected in the condenser 16 and to a less extent in the condenser 17 when effluent water in the sink had a very uniform frothy appearance as it ran to waste.

It was found that the oily product collected in the receivers 16 and 19 under some conditions amounted to about 100 per cent of the oil used, over and above the water which condensed with the product. According to one analysis the escaping gases contained 4 per cent CO_2 , 2.5 per cent O_2 , 1.1 per cent CO , and 1.6 per cent H_2 . The condensed oily product floated upon the condensed water and was separated therefrom by a clear line of demarkation. When agitating with water the frothing agent usually obtained by the above described procedure the froth produced appeared to be less dependent than are many froths upon the presence of metallic or metalliferous sulphide particles for sufficient persistence to allow its removal by the well known methods. In fact a froth of large and small bubbles which would last well was sometimes produced readily in the absence of sulphides or other solids. One oil used as a mineral-frothing agent and made from gas oil in the coke filled retort when used at the rate of 1.88 pounds per ton of ore yielded in a Janney machine a concentrate containing 20.53 per cent of zinc from Butte Superior zinc ore, assaying 12.74 per cent zinc, giving an extraction of 97.36 per cent. For modifying agents there were used with the oil per ton of ore 0.2 pound sulphuric acid, 0.5 pound copper sulphate and 1 pound sodium chloride.

I claim:

1. The process which consists in carrying

the vapor of a carbon compound together with oxygen in a confined space across heated carbonaceous material to produce substances condensable to an oily liquid largely absorbable by concentrated sulphuric acid. 65

2. The process which consists in flowing an oil into contact with heated carbonaceous material in the presence of a current 70 of air to produce substances condensable to an oily liquid largely absorbable by concentrated sulphuric acid, and collecting the product.

3. The process which consists in flowing 75 a carbon compound into contact with heated hard carbonaceous material in the presence of a current of air to produce substances condensable to an oily liquid largely absorbable by concentrated sulphuric acid, 80 and collecting the product.

4. The process which consists in flowing a carbon compound in a gas current carrying oxygen into contact with hard carbon material heated so as to maintain during 85 the reaction a temperature well over 200° C. above the carbonaceous material to produce substances condensable to an oily liquid largely absorbable by concentrated sulphuric acid, and collecting the product. 90

5. The process which consists in carrying the vapor of a carbon compound together with oxygen in a confined space across heated hard carbonaceous material to produce substances condensable to an oily liquid 95 largely absorbable by concentrated sulphuric acid.

6. The process which consists in flowing a petroleum distillate into contact with heated hard carbonaceous material in the 100 presence of a current of air to produce substances condensable to an oily liquid largely absorbable by concentrated sulphuric acid, and collecting the product.

7. The process which consists in flowing 105 a petroleum distillate into contact with heated hard carbonaceous material in the presence of a suitably regulated current of air to produce substances condensable to an oily liquid largely absorbable by concentrated sulphuric acid, 110 and collecting the product.

8. The process which consists in flowing a petroleum distillate into contact with heated hard carbonaceous material so that 115 the vaporized petroleum is carried in a confined space over the carbonaceous material in the presence of air to produce substances condensable to an oily liquid largely absorbable by concentrated sulphuric acid. 120

In testimony whereof, I have affixed my signature to this specification.

RHETHERFORD B. MARTIN.
